UNITED STATES PATENT OFFICE.

HENRY K. GILBERT, OF NIAGARA FALLS, NEW YORK, ASSIGNOR TO R. F. MORSE, OF PROVIDENCE, RHODE ISLAND.

DESIGN FOR A RUBBER GASKET.

SPECIFICATION forming part of Design No. 30,405, dated March 28, 1899.

Application filed March 1, 1899. Serial No. 707,407. Term of patent 7 years.

To all whom it may concern:

Be it known that I, HENRY K. GILBERT, a citizen of the United States, residing at Niagara Falls, in the county of Niagara and State of New York, have invented and produced a new and original Design for Rubber Gaskets; and I do hereby declare the following to be a full, clear, and exact description of the same, reference being had to the accompanying drawings, forming a part thereof.

In the drawings, Figure 1 represents a perspective view of the gasket. Fig. 2 is a central longitudinal section of the same.

The design relates to the configuration of the gasket.

The leading features of the design appear in the following description.

The gasket is formed with a body portion or flange, from opposite sides of which extend

the thin portions, which are at right angles to the said flange and which are of uniform thickness throughout, so that the inner and outer walls thereof are parallel with each other, as seen best in Fig. 2. The bore of the gasket is uniform throughout its entire length, being the same through the flange as through the thinner portions. The thin portions join with the flange portion to constitute an integral structure.

What is claimed as new is—

The design for a rubber gasket substantially as herein shown and described.

In testimony whereof I affix my signature in presence of two witnesses.

HENRY K. GILBERT.
